UNITED STATES PATENT OFFICE

HENRY KINNEY, OF SACRAMENTO, CALIFORNIA

MANUALLY-OPERATED ELECTRIC KEYBOARD

Application filed February 24, 1930. Serial No. 431,005.

My invention relates to improvements in manually operated electric keyboards, and it consists in the combinations, constructions and arrangements hereinafter described and claimed.

Perfect intonation requires that each of the twelve tones in an octave shall have four slightly different pitches or rates of vibration depending upon the key in which it is used. In other words, forty-eight tones to the octave must be provided if it is desired to play in all twelve keys. While only twelve tones to the octave are used at any one time, when modulating upward or downward by fifths it is necessary to discard three tones in each octave for each modulation and connect three new tones having a different pitch. To conveniently connect and disconnect the various tones in order to produce the proper assortment of tones to maintain perfect intonation in any key in which it is desired to play is the principal function of the apparatus about to be described.

Perfect intonation and the method of tuning is fully described in my United States Patent No. 1,743,458, issued January 14, 1930. For the present purpose a brief description will suffice, as follows: Establish the three tones A, C, and C sharp at 435, 522, and 543 $\frac{3}{4}$ vibrations per second respectively. Now from each of the three tones as a starting point, tune a separate series of absolutely perfect fifths and octaves above and below as far as desired or the full range of the instrument. This method of tuning gives all the tones necessary for every degree of the major and minor scales in all keys.

The A series gives all the keynotes also the degrees 2, 4, 5, 6 $\frac{1}{2}$, of both the major and true minor scales. The C series gives the degrees 1 $\frac{1}{2}$, 2 $\frac{1}{2}$, 4 $\frac{1}{2}$, 5 $\frac{1}{2}$, of the major scales and the degrees 3, 4 $\frac{1}{2}$, 6, 7, of the true minor scales. The C sharp series gives the degrees 3, 6, 7, of the major scales and the degrees 1 $\frac{1}{2}$, 2 $\frac{1}{2}$, 5 $\frac{1}{2}$, of the true minor scales. This is modulation by fifths. The true minor scale descends from the keynote by exactly the same series of tones and semitones as is used by the major scale in ascending from the keynote.

Other objects and advantages will appear as the specification proceeds, and the novel features of the invention will be particularly pointed out in the claims hereto annexed.

My invention is illustrated in the accompanying drawing, in which:

Figure 1 is a plan view of the device, portions being broken away for clarity,

Figure 2 is a transverse section through the device,

Figure 3 shows the arrangement of contacts for the major keys, and

Figure 4 is a plan view of a portion of the device.

In carrying out my invention I provide a frame indicated generally at 1 (see Figure 2). A keyboard 2 is slidably mounted in the frame and is carried by angle irons 3, these angle irons in turn being slidable over supporting rollers 4 (see Figures 1 and 2). The rollers are carried by the frame 1. The purpose of making the keyboard 2 slidable in the frame is to permit transposing from one key to another as set forth in my Patent No. 1,743,457, issued January 14, 1930.

The keyboard 2 carries a plurality of black and white push buttons. In Figure 1 I have shown one complete octave of white push buttons numbered 1 to 8 inclusive. Black push buttons or keys 5 are associated with the white push buttons or keys 6 in the usual manner. It is obvious that standard piano keys may be substituted for the push buttons if desired.

Each of the push buttons 5 and 6 carries a conductor point 7 (see Figure 2), and when the push button is depressed, this point contacts with a conductor strip 8 disposed directly therebeneath. I provide a number of these strips and arrange them in a predetermined manner on an insulating drum 9. The drum is hollow and the strips are preferably embedded in the drum.

I have shown the drum or cylinder 9 in two semi-cylindrical parts 9a and 9b. The purpose of this is to permit wires 10 to be connected to the various conductor blades 8 while the two parts are separated from each other. After the wires have been connected, the parts 9a and 9b may be secured to

the ring 11 by screws 12 or other suitable fastening means.

Each end of the cylinder 9 is mounted in a bearing 13. In Figure 1 I have shown the left-hand end of the instrument and have illustrated only one bearing. A similar bearing 13 is disposed at the opposite end for rotatively supporting the cylinder 9. The wires from the plates 8 pass out through a cable 14 and are connected to any sounding mechanism desired.

The plates 8 are arranged so as to connect the proper note sounding devices with the push buttons 5 and 6 in order to provide perfect harmony. In my United States Patent No. 1,743,458 issued January 14, 1930, I set forth that four tones are necessary for each key in order that the device will play in perfect harmony for any key. The plates 8 are so arranged on the drum 9 as to automatically make the proper note producing devices for the particular key played.

In Figure 3 I have shown all of the contact plates 8 necessary for producing the proper electrical connections for the keys ranging from A flat major to G sharp major. These plates 8 are disposed on one-half of the cylinder 9, i. e. on the half 9a. The groups of plates 8 indicating the minor keys are placed on the lower half 9b of the cylinder. Both groups of plates are identical in arrangement except that the minor plates are arranged in reverse order to that of the major plates. To make this perfectly clear, it can be said that if Figure 3 were drawn on a transparent sheet of paper and then this paper held to the light and viewed from the reverse side, it would show an accurate representation of the minor plates 8.

At the left hand end of the drum 9 I mount an indicator 15 which bears the letters from A flat to G sharp. The lower half of the same indicator bears similar letters, but these indicate the minor keys. The indicator rotates with the drum 9, and a pointer 16 carried by the frame 1 designates what group of conductor blades 8 are disposed beneath the keys 5 and 6. In the position shown in Figure 1, the pointer 16 indicates that the C major groups of plates 8 are disposed beneath the keys 5 and 6.

The drum 9 and the indicator 15 are rotated by means of a worm gear 17 (see Figure 1) that is mounted on the drum 9, this gear meshing with a worm 18 (see Figure 2). The worm is mounted upon a shaft 19, and the latter is supported by bearings 20. The shaft projects through the front wall of the casing 1 and passes through a disc 21 that is secured to the frame 1. A second disc 22 (see Figure 1) is rigidly secured to the shaft 19 so that a rotation of this disc will rotate the shaft. A spring arm 23 is connected to the disc 22 and the shaft 19 so that a swinging of the arm about the axis

of the shaft 19 as a center will rotate the disc 22 and also the shaft. A handle 24 is secured to the spring arm 23 and carries a pin 25 that is adapted to enter a recess 26 in the disc 21. From this construction it will be seen that the operator in rotating the drum 9 first manually pulls the handle 24 toward himself, flexing the spring 23 and removing the pin 25 from the recess 26. While still holding the spring 23 in flexed position, the operator rotates the handle 24 through one complete revolution and then allows the pin 25 to again enter the recess 26. This will rotate the drum 9 one-thirty-second of a revolution, which is sufficient to change the position of the contact plates 8 from one key to another, for example, from the key of C to the key of G.

The drum 9 is provided with a stop 27 (see Figure 2). This stop contacts with a stop 28 carried by the frame 1 so as to allow the drum to make one complete revolution, after which the drum must be rotated in the opposite direction. If the drum were permitted to rotate continuously in one direction, the wires 10 would be twisted and would in time break.

From the foregoing description of the various parts of the device, the operation thereof may be readily understood.

Assume that the drum 9 is rotated to the position for the scale A flat. The plates 8 struck by the contact points 7 while the drum is in this position will connect wires 10 to such tones of the instrument as will produce perfect intonation in the key of A flat major. Now if it is desired to play in the key of E flat or, in other words, to modulate to a fifth higher, the modulating shaft 19 is turned one complete revolution in a counter-clockwise direction, thus rotating the drum 9 one-thirty-second of a revolution so that the contact points 7 will strike the plates 8 associated with the key E flat major.

A careful inspection of Figure 3 will show that nine of the contact points 7 in each octave still strike on the same plates 8 as they did in the key of A flat, while three in each octave strike on new plates 8 connected to tones of the instrument or instruments having a different pitch. The three new tones are F, F sharp, and D. The new tones F and F sharp are a Didymus comma sharper (ratio 81-80) than the old tones F and F sharp, and the new tone D is a diachisma flatter (ratio 81 to 81.92) than the old tone D.

Now if it is desired to modulate a fifth higher into the key of B flat, the modulating shaft 19 is turned another complete revolution, thus connecting three new tones in each octave, in this case C, C sharp, and A. The new tones C and C sharp are a Didymus comma sharper and the new tone A is a diachisma flatter than the discarded tones. Thus, when modulating upward by fifths de-

grees 2 and 2½ of the new major scale must be sharpened a Didymus comma and the seventh degree flattened a diaschisma to maintain perfect intonation.

5 When modulating downward by fifths the tones, of course, are connected and disconnected in the reverse order. The player can modulate by thirds or any other desired interval, the rule being to take the desired key 10 wherever you find it on the modulating index. The key obtained will always be in perfect intonation, but the distance modulated may be a small fraction more or less than the perfect interval. (Generally a 15 Didymus comma, never more than a Pythagorean comma.) When modulating by fifths, the distance modulated is an absolutely perfect fifth.

The device is shown with a transposing 20 keyboard which has been described and claimed in United States Patent No. 1,743,457 issued January 14, 1930. The structure as shown in this application will be briefly described as follows: The left-hand 25 angle iron 3 in Figure 2 carries a rack 29. This rack meshes with a large gear 30 rotatably carried by the frame 1, and the gear 30 in turn meshes with a small gear 31. The small gear 31 is mounted on a shaft 32 as 30 shown in Figure 1, and this shaft is rotatable by a handle 33 similar to the handle 24. A disc 34 similar to the disc 21 is secured to the frame 1, and I have shown this disc in Figure 4 to illustrate the number of openings 35 provided in it. The pin 36 carried by the handle 33 is removably receivable in any one of the openings 35.

The frame 1 carries a scale 37 for indicating different minor keys and a scale 38 indicating different major keys. The movable 40 keyboard has a scale 39 associated with the scale 37 and a scale 40 associated with the scale 38. The movable keyboard is shown in position for playing C major.

45 To adjust the keyboard to play in the desired key, actuate the handle 33 for sliding the keyboard until the movable index letter on the scale 40 representing the key in which the music is written comes opposite the stationary index letter on the scale 38, this latter letter indicating the key into which it is desired to transpose the music. If a minor scale is desired, the scales 37 and 39 are used.

The music is now played in exactly the 55 same way as it is written, and the instrument will automatically transpose the music into the desired key.

Another big advantage of the transposing 60 keyboard is that all music may be written and played in the easiest natural key and the keyboard so adjusted that the music produced will be in its proper key as intended by the composer. Thus the player need learn the scale, chords, fingering, etc., of one 65 key only instead of the twelve or twenty-

four different scales of the present systems. It should be noted that the modulator 15 must be kept adjusted to the key in which the music is being produced whether transposing or not. If the song is being played in the scale of D, the modulator is turned until the letter D is positioned opposite the pointer 16.

70 The transposing disc 34 has twelve openings 35 therein, these openings being uniformly spaced around a circle or thirty degrees apart. If desired, the transposing index may be placed on the disc 34.

75 Lines 8a represent the division point between the keys A flat to G sharp of Figure 3.

80 Although I have shown and described one embodiment of my invention, it is to be understood that the same is susceptible of various changes, and I reserve the right to employ such changes as may come within the 85 scope of the invention as claimed.

I claim:

1. A manually operated electric keyboard comprising a plurality of manually movable electric contacts, a plurality of contacts 90 electrically connected to sound producing members, means for moving different groups of the second-named contacts beneath the first named contacts where they will be engaged upon the manual movement of the 95 first-named contacts.

2. In a manually operated electric keyboard, a plurality of manually movable electric contacts, push buttons for the contacts and arranged in the same manner as a piano 100 keyboard, and a plurality of contacts movable into positions where they will be engaged by the first contacts when actuated, there being four of the second contacts for each one of the first.

3. A manually operated electric keyboard comprising a plurality of keys, four contacts for each key, means for moving any one of the contacts into a position to be struck by the depression of the associated key, and 110 means for moving the keys into a position to be associated with a different set of contacts.

4. A manually operated electric keyboard comprising a frame, a key carrying member 115 slideable on the frame, keys carried by the frame, a drum carrying a plurality of contacts, means for moving the member into the desired position, and means for rotating the drum for bringing the desired contacts into a position to be engaged by said keys.

5. A manually operated electric keyboard comprising a frame, a key carrying member slideable on the frame, keys carried by the frame, a drum carrying a plurality of contacts, means for moving the member into the 125 desired position, and means for rotating the drum for bringing the desired contacts into a position to be engaged by said keys, said drum having four contacts for each key.

6. In an electric musical instrument, a 130

member carrying a plurality of contacts, said member having four contacts for each key, and means for moving the member for bringing the desired contacts into a position to be engaged by the keys.

- 5 7. In an electric musical instrument, a member carrying a plurality of contacts, said member having four contacts for each key, and means for moving the member for bringing the desired contacts into a position to be engaged by the keys, and an indicator associated with the member for showing the scale being played.
